TUBULATION AND LEAD-IN CONSTRUCTION

Hampton J. Dailey, deceased, late of Verona, N. J.,
by Ruth M. Dailey, executrix, Verona, N. J., as-
signor to Westinghouse Electric Corporation,
East Pittsburgh, Pa., a corporation of Pennsyl-
vania

Application April 29, 1952, Serial No. 284,912

5 Claims. (Cl. 174—17.07)

1

This invention relates to tubulation and lead-in construction for use with electronic devices which have evacuated envelopes and electrodes therein requiring lead-in connections from the exterior of the envelopes.

In the design of electronic tubes, the tubulation or connection to the pumping system for evacuating the tubes has usually been of glass. This glass connection is fragile and extreme care is necessary to prevent the glass being stressed; otherwise fracture may result. When the tube is tipped off from the system adsorbed gas and water vapor in the glass are unavoidably released into the tube, which is undesirable. The designing of connections between tube electrodes and external terminals which may be easily made without displacing the tube electrodes or placing strain on the glass seal is difficult, with such connections usually being made by compression fittings such as bolts or eyelets or by spot welding. Compression joints are particularly unreliable and often lead to "hot spotting" or high resistance joints. Spot welding often leads to strains in the welded metals which often result in displaced electrodes.

An object of the present invention is to provide an improved construction combining the tubulation and the lead-in connection for one of the electrodes.

Another object is to utilize the sealing of the tubulation to also secure the lead-in connection.

A further object of the invention is to provide a tubulation and lead-in construction which imposes no detrimental strains and yet is easily constructed and fully effective.

Other objects of the invention will appear to persons versed in the art to which it appertains as the description proceeds, both by direct reference thereto and by implication from the context.

Referring to the accompanying drawing in which the numerals of reference indicate similar parts throughout the several views:

Figure 1 is an elevational section of an electronic device showing the invention incorporated therein;

Figure 2 is a longitudinal sectional view of the tubulation in process of fabrication;

Figure 3 is a cross-section on line III—III of Figure 2; and

Figure 4 is a longitudinal sectional view of a modified construction of lead-in connection.

In the specific embodiment of the invention illustrated in said drawing, there is shown, by way of example, an electron discharge device which

2

comprises a glass or other ceramic bowl 10, here represented as part of an evacuated envelope, a metallic dome-like anode 11 being sealed in the rim thereof to constitute the complementary part 5 of said envelope. For convenience of reference, said glass bowl 10 will be considered as the base portion of the envelope. From the bottom of this bowl or base protrude a plurality of thimbles 12 of similar character and constituting prongs 10 as a means for making exterior circuit connections and for support of the device. Protruding centrally from the bottom of the bowl or base, differing somewhat from the other prongs 12 is a prong 13 wherein the present invention is exemplified and which will be described more in detail hereinafter.

The electron device includes therein a grid 14 and cathode 15, here shown of filamentary type, and having a common center post 16 for support at their upper ends. The post is a conductor and external connection is made through the aforementioned central prong 13. The other prongs 12 have appropriate internal connections to the lower ends of the filaments and one to the 25 grid.

Said nipple or prong 13 is fabricated to function initially as the exhaust tubulation and ultimately as an external terminal for a lead-in connection. As shown, said nipple comprises a 30 copper or other suitable collar 17 having a rim thereof sealed to the margin of an opening 18 provided in the glass of bowl 10. One mode of effecting a seal is to feather-edge said margin of the metal collar as it will respond to the expansion and contraction of the glass without developing cracks and leaks, and this type of seal has been arbitrarily selected for illustrative purposes. Below the feather edge portion of the 35 collar, the same is shouldered inward as at 19 to a smaller diameter of passageway, and below the shoulder is constituted as a depending hollow neck 20.

Referring more particularly to Figures 1 to 3, a metal tube 21 is located within said neck and protrudes at both ends therefrom. This tube is 45 preferably copper and of appropriate diameter to fit in the neck 20 of collar 17 to which it is sealed by solder 22 or other suitable means. This uniting of the collar and tube is preferably performed before the collar is sealed to the glass bowl. A lead-in connection 23 extends from the cathode center post 16 downward into the tube 21 for a distance well below the shoulder 19 of the surrounding collar 17, and by preference said lead-in connection is a flat strip of copper, and

leaves adequate passageway within the tube for enabling the tube to function as an exhaust tubulation. The lower end of said tube may be connected to the pumping system and the electronic device thereby exhausted. When the pumping cycle is completed, tube 21 is pinched by a pair of pinching jaws 24. This pinching operation is preferably in a direction toward the flat faces of the lead-in connection 23 contained within the tube. The pinching operation is accomplished with adequate pressure to obtain a cold welding of the flattened portion of the tube and with the lead-in connection so as to obtain a perfect vacuum-tight seal of the tube and electrical continuity of tube and lead-in connection. The pressure applied to the pinching jaws is adequate to cold-flow the copper, or other material of which the tube and lead-in connection are composed, and to pinch-off the ends thereof, and is of the order of several thousand pounds. By this mode of sealing the tubulation, use of applied heat is avoided and thus avoids heat stresses in the glass and avoids generation or release within the device of gas and water vapor which are accompanying evils with sealing by applied heat. Furthermore, this mode of sealing assures perfect and permanent electrical contact between the tube and the lead-in connection.

After the tubulation has been sealed as above described, it is enclosed within a housing or thimble 25 making electrical contact therewith. This thimble is shown as shouldered to seat against the collar shoulder and flared thereabove to provide a corona shield 26 around the feather-edge seal of the collar and glass. Since the thimble, tube and collar are all metal, the thimble may have a filler 27 of solder therein at the part thereof below the shoulder thereby obtaining secure attachment and good electrical connection.

While the foregoing description has given an example of strip formation of the lead-in connection, the invention is equally applicable to tubular lead-in connection, this being included in the showing of Fig. 4. That modification provides a copper or other tube 21a which has an opening 28 within the device so as to be usable as the exhaust tubulation, and this tube may extend upwardly in the device, in place of the strip 23 of Fig. 1, and constitute a lead-in connection to an electrode or part connected therewith. In this particular embodiment of Fig. 4, the neck 20a of collar 17a is shown extending along the tube far enough to be pinched off therewith thereby effecting rigid mechanical attachment and good electrical connection. The high pressure of the pinching jaws obtains a cold flow of the metals of both the tube and collar neck effecting a weld therebetween as well as a sealing closure of each. Exterior thimble and corona shield of Fig. 1 is equally applicable to the construction of Fig. 4.

What is claimed is:

1. An electron discharge device having a basal

portion with an opening therein for exhaust purposes, a collar sealed to the margin of said opening, said collar having a sholuder and outwardly protruding neck therefrom and an exhaust tubulation in part within said collar and passing through and secured to said neck, the outer end of said exhaust tubulation having a cold-weld pinched closure.

2. An electron discharge device having a basal portion with an opening therein, a collar sealed to the margin of said opening, an exhaust tubulation in part within said collar and secured thereto, the outer end of said tubulation having a cold-weld pinched closure, and a thimble enclosing said outer end of the tubulation, said thimble being secured to said collar.

3. An electron discharge device having a basal portion with an opening therein, a collar sealed to the margin of said opening, an exhaust tubulation in part within said collar and secured thereto, the outer end of said tubulation having a cold-weld pinched closure, and a thimble enclosing said outer end of the tubulation, said thimble being secured to said collar and said thimble having a corona shield extending therefrom toward and surrounding the sealed margin of said collar and opening.

4. A structural unit for an electron discharge device, comprising two metallic members of which one of said members is tubular and contains a part of the other, and said members being contiguous to each other for a substantial portion of the length of said tubular member and secured together at a pinched-off end of the tubular member with the inner of said members within the said pinched-off end of the tubular member.

5. A structural unit for an electron discharge device, comprising two metallic members of which one of said members is tubular and contains a part of the other, and said members being contiguous to each other for a substantial portion of the length of said tubular member and secured together at a pinched-off end of the tubular member with the inner of said members within the said pinched-off end of the tubular member, and with the metal of the two members at said pinched-off end unified by a cold-welding thereof.
